LIGHT EMITTING CHIP INCLUDING A PLURALITY OF LIGHT EMITTING UNITS AND IMAGE FORMING

BACKGROUND OF THE INVENTION

Field of the Invention

The present invention relates to a light emitting chip including a plurality of light emitting units, and an image forming apparatus that forms an image using the light emitting chip.

Description of the Related Art

An electrophotographic image forming apparatus forms an electrostatic latent image on the photoconductor by exposing a rotationally driven photoconductor, and forms an image by developing the electrostatic latent image with toner. Here, a direction parallel to the rotation axis of the photoconductor is referred to as a main scan direction. Japanese Patent Laid-Open No. 2021-035765 discloses an image forming apparatus that performs exposure by using an exposure apparatus including a plurality of columns of light emitting units arranged in a sub scan direction corresponding to a rotation direction of a photoconductor, in which each column includes a plurality of light emitting units arranged in a main scan direction. In Japanese Patent Laid-Open No. 2021-035765, flip-flop circuits configured to hold image data are respectively provided in corresponding number as number of light emitting units, and when image data is held in all the flip-flop circuits, control of the light emitting units are performed all at once. Accordingly, there is a concern in the aforementioned exposure head that simultaneously turning on a large number of light emitting units may cause electrical noise such as switching noise to increase.

SUMMARY OF THE INVENTION

The present disclosure reduces occurrence of electrical noise due to simultaneously turning on a plurality of light emitting units in an image forming apparatus including an exposure head provided with a plurality of light emitting units.

According to an aspect of the present invention, a light emitting chip includes: a light emitting unit array including a plurality of light emitting units arranged in a predetermined direction; an image data input terminal configured to be input an image data; a first data storage unit configured to store data, input from the image data input terminal, for causing a first light emitting unit included in the plurality of light emitting units to emit light; a second data storage unit configured to store data, input from the image data input terminal, for causing a second light emitting unit included in the plurality of light emitting units to emit light; a signal output unit configured to output a first trigger signal and a second trigger signal delayed with respect to the first trigger signal; and a drive unit configured to drive the first light emitting unit, in a case where the first trigger signal is output, based on data stored in the first data storage unit, and drive the second light emitting unit, in a case where the second trigger signal is output, based on data stored in the second data storage unit.

Further features of the present invention will become apparent from the following description of exemplary embodiments with reference to the attached drawings.

BRIEF DESCRIPTION OF THE DRAWINGS

- FIG. 1 is a schematic configuration diagram of an image forming apparatus according to an embodiment;
- 5 FIGS. 2A and 2B are diagrams illustrating an exposure head and a photoconductor according to an embodiment;
- FIGS. 3A and 3B are diagrams illustrating a printed substrate of an exposure head according to an embodiment;
- 10 FIG. 4 is an explanatory diagram of an arrangement of light emitting elements in a light emitting chip, according to an embodiment;
- FIG. 5 is a plan view of a light emitting chip, according to an embodiment;
- 15 FIG. 6 is a cross sectional view of a light emitting chip, according to an embodiment;
- FIG. 7 is a control configuration diagram of a light emitting chip, according to an embodiment;
- 20 FIG. 8 is diagram illustrating example signals on respective signal lines when a register of a light emitting chip is accessed, according to an embodiment;
- FIG. 9 is diagram illustrating example signals on respective signal lines when image data is transmitted to a light emitting chip, according to an embodiment;
- 25 FIG. 10 is a functional block diagram of a light emitting chip, according to an embodiment;
- FIG. 11 is a configuration diagram of a transfer unit, according to an embodiment;
- FIG. 12 is a configuration diagram of a latch unit, according to an embodiment;
- 30 FIG. 13 is a configuration diagram of another latch unit, according to an embodiment;
- FIG. 14 is a timing chart of signals in a circuit unit, according to an embodiment;
- 35 FIG. 15 is a configuration diagram of a current drive unit according to an embodiment;
- FIG. 16 is a flowchart of processing executed by an image controller, according to an embodiment; and
- 40 FIG. 17 is another timing chart of signals in a circuit unit according to an embodiment.

DESCRIPTION OF THE EMBODIMENTS

Hereinafter, embodiments will be described in detail with reference to the attached drawings. Note, the following embodiments are not intended to limit the scope of the claimed invention. Multiple features are described in the embodiments, but limitation is not made to an invention that requires all such features, and multiple such features may be combined as appropriate. Furthermore, in the attached drawings, the same reference numerals are given to the same or similar configurations, and redundant description thereof is omitted.

First Embodiment

FIG. 1 is a schematic configuration diagram of an image forming apparatus according to the present embodiment. A reading unit 100 reads a document placed on a document plate and generates image data representing a reading result. An image creating unit 103 forms an image on a sheet based on, for example, the image data generated by the reading unit 100 or image data received from an external apparatus via a network.

The image creating unit 103 includes image forming units 101a, 101b, 101c and 101d. The image forming units 101a, 101b, 101c and 101d respectively form black, yellow, magenta and cyan toner images. The image forming units

101a, 101b, 101c and 101d have a similar configuration and therefore will be collectively referred to as an image forming unit **101**. In forming an image, a photoconductor **102** of the image forming unit **101** is rotationally driven in a clockwise direction of the diagram. A charger **107** charges the photoconductor **102**. An exposure head **106**, which is an exposure apparatus, exposes the photoconductor **102** in accordance with the image data, and forms an electrostatic latent image on the photoconductor **102**. A developer **108** develops the electrostatic latent image on the photoconductor **102** with toner. The toner image formed on the photoconductor **102** is transferred onto a sheet that is conveyed on a transfer belt **111**. Here, different colors from black, yellow, magenta and cyan can be reproduced by transferring toner images formed on respective photoconductors **102** onto a sheet in an overlapping manner.

A conveyance unit **105** controls feed and conveyance of a sheet. Specifically, the conveyance unit **105** feeds a sheet to the conveyance path of the image forming apparatus from a unit specified among internal storage units **109a** and **109b**, an external storage unit **109c**, and a manual feed unit **109d**. The sheet being fed is conveyed to a registration roller **110**. The registration roller **110** conveys the sheet onto the transfer belt **111** at a predetermined timing such that toner images formed on respective photoconductors **102** are transferred onto the sheet. As has been described above, the toner images are transferred onto the sheet while the sheet is being conveyed on the transfer belt **111**. A fixing unit **104** heats and pressurizes the sheet, on which the toner images are transferred, to fix the toner images on the sheet. After the toner images are fixed, the sheet is discharged by a discharge roller **112** to the outside of the image forming apparatus.

FIGS. 2A and 2B illustrate the photoconductor **102** and the exposure head **106**. The exposure head **106** includes a light emitting point group **201**, a printed substrate **202** in which the light emitting point group **201** is mounted, a rod lens array **203**, and a housing **204** that supports the rod lens array **203** and the printed substrate **202**. The rod lens array **203** focuses the light emitted from the light emitting point group **201** onto the photoconductor **102** to form an imaging spot of a predetermined size on the photoconductor **102**.

FIGS. 3A and 3B illustrate the printed substrate **202**. Here, FIG. 3A illustrates a surface on which a connector **305** is mounted, and FIG. 3B illustrates a surface on which the light emitting point group **201** is mounted (an opposite surface to the surface on which the connector **305** is mounted). In the present embodiment, the light emitting point group **201** includes 20 light emitting chips **400-1** to **400-20**. The light emitting chips **400-1** to **400-20** are arranged in two staggered columns along the main scan direction. In the following description, the light emitting chips **400-1** to **400-20** will also be collectively referred to as light emitting chips **400**. Each of the light emitting chips **400** includes a plurality of light emitting points (light emitting elements). Each of the light emitting chips **400** of the printed substrate **202** is connected, via a connector **305**, to an image controller **700** (FIG. 7), which is a control unit.

FIG. 4 is an explanatory diagram of an arrangement of the light emitting chips **400** and light emitting points **602** provided on the light emitting chips **400**. One light emitting chip **400** includes a plurality of sets of 748 light emitting points **602** arranged along the main scan direction. Here, the plurality of sets are arranged along a sub scan direction orthogonal to the main scan direction. As such, the light emitting chips **400** are arranged two-dimensionally along both the main scan direction and the sub scan direction. In other words, the light emitting points **602** may be arranged

by including M rows in the circumferential direction of the photoconductor and N columns in the axial direction of the photoconductor. In the following description, the number of sets is assumed to be four, as an example. In other words, it is assumed in the following exemplary embodiment that the light emitting chips **400** include four sets of 748 light emitting points **602** arranged along the main scan direction, i.e., a total of 2992 light emitting points **602**. The pitch of the light emitting points **602** adjacent to each other in the main scan direction is about 21.16 μ m, which corresponds to a resolution of 1200 dpi. Therefore, the length of one set of 748 light emitting points **602** in the main scan direction is about 15.8 mm. In addition, the pitch (length P in FIG. 4) of the light emitting points **602** adjacent to each other in the sub scan direction is about 21.16 μ m, which corresponds to a resolution of 1200 dpi. Furthermore, the pitch (length L in FIG. 4) between the light emitting points **602** of two light emitting chips **400** adjacent to each other in the main scan direction is about 21.16 μ m, which corresponds to a resolution of 1200 dpi.

FIG. 5 is a plan view of the light emitting chip **400**. The plurality of light emitting points **602** of the light emitting chip **400** are formed, for example, on a light emitting substrate **402**, which is a silicon substrate. Furthermore, a circuit unit **406** configured to control the plurality of light emitting points **602** is formed on the light emitting substrate **402**. A signal line configured to communicate with the image controller **700**, a power line configured to connect to a power source, and a ground line configured to connect to the ground will be connected to pads **408-1** to **408-9**. The signal line, the power line, and the ground line are wires made of gold, for example.

FIG. 6 illustrates a part of a cross section taken along line A-A in FIG. 5. A plurality of lower electrodes **504** are formed on the light emitting substrate **402**. A gap of a length d is provided between two adjacent lower electrodes **504**. A light emitting layer **506** is provided on the lower electrodes **504**, and an upper electrode **508** is provided on the light emitting layer **506**. The upper electrode **508** is one common electrode for the plurality of lower electrodes **504**. When a predetermined voltage is applied between the lower electrode **504** and the upper electrode **508**, electric current flows from the lower electrode **504** to the upper electrode **508**, and thus the light emitting layer **506** emits light. Therefore, a region of the light emitting layer **506** corresponding to a region of one lower electrode **504** corresponds to one light emitting point **602**. In other words, the light emitting substrate **402** of the present embodiment includes a plurality of light emitting points. Here, the light emitting point may also be referred to as a light emitting unit. A light emitting unit array including a plurality of light emitting units arranged in the main scan direction is formed in each of the light emitting chips **400**.

Organic EL film, for example, may be used for the light emitting layer **506**. Alternatively, an inorganic EL film may be used for the light emitting layer **506**. The upper electrode **508** is formed of, for example, a transparent electrode made of indium tin oxide (ITO) or the like, for transmitting the emission wavelength of the light emitting layer **506**. Although the whole of the upper electrode **508** transmits the emission wavelength of the light emitting layer **506** in the present embodiment, the whole of the upper electrode **508** needs not transmit the emission wavelength. Specifically, a part of the upper electrode **508** corresponding to a region where light is emitted from each light emitting point **602** may transmit the light emission wavelength.

Although one continuous light emitting layer **506** is formed in FIG. 6, a plurality of light emitting layers **506**

each having the similar width as the width W of the lower electrode 504 may be respectively formed on the lower electrode 504. In addition, although the upper electrode 508 is one common electrode for the plurality of lower electrodes 504 in FIG. 6, a plurality of upper electrodes 508 each having the similar width as the width W of the lower electrode may be formed as corresponding to each of the lower electrodes 504. Alternatively, a first plurality of lower electrodes 504 among the lower electrodes 504 of each of the light emitting chips 400 may be covered by a first light emitting layer 506, and a second plurality of lower electrodes 504 may be covered by a second light emitting layer 506. Alternatively, a first upper electrode 508 may be commonly formed as corresponding to a first plurality of lower electrodes 504 and a second upper electrode 508 may be commonly formed as corresponding to a second plurality of lower electrodes 504, among the lower electrodes 504 of each of the light emitting chips 400. Also in the aforementioned configuration, one lower electrode 504, a region of the light emitting layer 506 and the upper electrode 508 corresponding to the one lower electrode 504 form one light emitting point (light emitting element) 602. Here, the light emitting point 602 may also be referred to as a light emitting unit.

FIG. 7 illustrates a control configuration of the light emitting chips 400. A data switching unit 705 and each of the light emitting chips 400 are connected by a plurality of signal lines (wires). Specifically, the data switching unit 705 and the light emitting chip 400-n (n being an integer from 1 to 20) are connected by a signal line DATA_n and a signal line WRITE_n. The signal line DATA_n is used by the data switching unit 705 to transmit image data to the light emitting chip 400-n. The signal line WRITE_n is used by the data switching unit 705 to write control data to a register of the light emitting chip 400-n.

In addition, the data switching unit 705 and all the light emitting chips 400 are connected by one signal line CLK, one signal line SYNC, and one signal line EN. The signal line CLK is used for transmitting a clock signal for data transmission in the signal lines DATA_n and WRITE_n. The data switching unit 705 outputs, to the signal line CLK, a clock signal generated based on a reference clock signal from a clock generator 702. Signals transmitted to the signal line SYNC and the signal line EN will be described below.

A CPU 701 controls the image forming apparatus 100 as a whole. An image data generation unit 703 performs various types of image processing such as halftone processing on the image data received from the reading unit 100 or an external apparatus, and generates image data for performing ON/OFF control of light emission from the light emitting point 602 of each of the light emitting chips 400. The image data generation unit 703 transmits the generated image data to the data switching unit 705. A register access unit 704 receives, from the CPU 701, control data to be written to the register of each of the light emitting chips 400, and transmits the control data to the data switching unit 705.

FIG. 8 illustrates signals of the respective signal lines when control data is written to registers of the light emitting chips 400. An enable signal, which rises to a high level indicating in-communication during communication, is output to the signal line EN. The data switching unit 705 transmits a start bit to the signal line WRITE_n in synchronization with the rising of the enable signal. Subsequently, the data switching unit 705 transmits a write identification bit indicating write operation, and subsequently transmits an address (4 bits in the present example) of the register, to which control data is written, and control data (8 bits in the

present example). In writing to the register, the data switching unit 705 set the frequency of the clock signal transmitted to the signal line CLK to be 3 MHz, for example.

FIG. 9 illustrates signals of respective signal lines when image data is transmitted to each of the light emitting chips 400. A cyclic line synchronization signal indicating an exposure timing of one line in the photocoupler 102 is output to the signal line SYNC. Assuming that the circumferential speed of the photocoupler 102 is 200 mm/s and the resolution in the sub scan direction is 1200 dpi (about 21.16 μ m), the line synchronization signal is output at a cycle of about 105.8 μ s. The data switching unit 705 transmits the image data to signal lines DATA1 to DATA20 in synchronization with the rising of the line synchronization signal. In the present embodiment, since each of the light emitting chips 400 includes 2992 light emitting points 602, it is necessary to transmit image data, to each of the light emitting chips 400, indicating emission/non-emission of light for each of a total of 2992 light emitting points 602 within a cycle of about 105.8 μ s. In order to transmit image data for a total of 2992 light emitting points 602 within a period of about 105.8 μ s, the data switching unit 705 sets, in transmitting image data, the frequency of the clock signals transmitted to the signal line CLK to 30 MHz in the present example, as illustrated in FIG. 9.

FIG. 10 is a functional block diagram of one light emitting chip 400-n. As also illustrated in FIG. 5, the light emitting chip 400 includes nine pads 408-1 to 408-9. The pads 408-1 and 408-2 are connected to a power supply voltage VCC by a power line. Electric power is supplied to each circuit of the circuit unit 406 of the light emitting chips 400 by the power supply voltage VCC. The pads 408-3 and 408-4 are connected to the ground by a ground line. Each circuit of the circuit unit 406 and the upper electrode 508 are connected to the ground via the pads 408-3 and 408-4. The signal line CLK is connected to a transfer unit 1003, a register 1102, and latch units 1004-001 to 1004-748 via the pad 408-5. The signal lines SYNC and DATA_n are respectively connected to the transfer unit 1003 via the pads 408-6 and 408-7. In other words, the pad 408-6 corresponds to a synchronization signal input terminal, and the pad 408-7 corresponds to an image data input terminal. The signal lines EN and WRITE_n are respectively connected to the register 1102 via the pads 408-8 and 408-9. As has been described above, the register 1102 stores control data indicating control information. Details of the control information will be described below.

In the following, the operation of the transfer unit 1003 and the latch units 1004-001 to 1004-748 (also collectively referred to as latch units 1004) will be described, referring to FIGS. 11 to 14. Here, it is assumed that the transfer unit 1003 receives, with the line synchronization signal from the signal line SYNC as a starting point and in synchronization with the clock signal, pieces of image data each indicating emission/non-emission of light of one light emitting point 602 in the order of D1, D2, D3, D2992. FIG. 14 illustrates a state in which the transfer unit 1003 has received pieces of image data D1 to D12.

FIG. 11 is a configuration diagram of the transfer unit 1003. A clock signal from the signal line CLK, a line synchronization signal from the signal line SYNC, and image data from the signal lines DATA_n are input to the transfer unit 1003. D flip-flops 1101-1 to 1101-8 operate in accordance with the clock signal. The D flip-flop 1101-1 sequentially outputs the image data received from DATA_n to a signal line PDATA4. The D flip-flop 1101-2 outputs the image data received from DATA_n to a signal line PDATA3 by delaying one clock from the image data output from the

D flip-flop **1101-1**. Similarly, the D flip-flops **1101-3** and **1101-4** output the image data received from DATA_n to signal lines PDATA₂ and PDATA₁ by respectively delaying two clocks and three clocks from the image data output from the D flip-flop **1101-1**.

FIG. 14 illustrates image data output from the transfer unit **1003** to the signal lines PDATA₁ to PDATA₄. As illustrated in FIG. 14, the transfer unit **1003** outputs the pieces of image data D₃, D₂ and D₁ respectively to the signal lines PDATA₃, PDATA₂ and PDATA₁ at the timing when the transfer unit **1003** outputs the piece of image data D₄ to the signal line PDATA₄. More generally, the transfer unit **1003** outputs the pieces of image data D_(4m-1), D_(4m-2) and D_(4m-3) respectively to the signal lines PDATA₃, PDATA₂ and PDATA₁ at the timing when the transfer unit **1003** outputs the piece of image data D_(4m) to the signal line PDATA₄, where m being an integer from 1 to 748.

The transfer unit **1003** delays the line synchronization signal by the D flip-flops **1101-5** to **1101-8**, and outputs a first latch signal to a signal line LAT₁ at a timing when the transfer unit **1003** outputs D₄ to the signal line PDATA₄.

FIG. 12 is a configuration diagram of the latch unit **1004-001**. D flip-flops **1202-1** to **1202-4** and latch circuits **1201-1** to **1201-4** operate in accordance with the clock signal from the signal line CLK. The image data from the signal lines PDATA₄ to PDATA₁ and the first latch signal from the signal line LAT₁ are input to the latch circuits **1201-1** to **1201-4**. Upon receiving the first latch signal from the signal line LAT₁, the latch circuits **1201-1** to **1201-4** latch the values being output to the signal lines PDATA₄ to PDATA₁ at that time, and output drive signals based on the latched values to the signal lines PON₁₋₄ to PON₁₋₁, as illustrated in FIG. 14. That is, the latch circuits **1201-1** to **1201-4** store the input image data, and output drive signals based on the stored image data. In other words, the latch circuits **1201-1** to **1201-4** correspond to a first data storage unit or a plurality of data storage units. Furthermore, the first latch signal corresponds to a first trigger signal. According to FIG. 14, the signal lines PON₁₋₁ to PON₁₋₄ output drive signals based on the pieces of image data D₁ to D₄. In the present embodiment, one light emitting chip **400** includes the structure in which four sets of 748 light emitting points **602** arranged along the main scan direction are arranged along the sub scan direction, as has been described referring to FIG. 4. For example, the light emitting points **602** of each set are numbered 1 to 748 along the X direction in FIG. 5 (corresponding to the main scan direction). In this case, the respective drive signals output to the signal lines PON₁₋₄ to PON₁₋₁ are drive signals of each first light emitting point **602** of the four sets. The drive signals are input to the current drive unit **1104**. The latch unit **1004-001** maintains outputting drive signals based on the pieces of image data D₁ to D₄ until receiving a first latch signal based on the next line synchronization signal. In other words, the drive signals based on the pieces of image data D₁ to D₄ are output for the duration of two consecutive line synchronization signals (about 105.8 μ s in the present example). In addition, the latch unit **1004-001** delays the first latch signal by the D flip-flops **1202-1** to **1202-4**, and outputs a second latch signal to a signal line LAT₂ at a timing when the transfer unit **1003** outputs D₈ to the signal line PDATA₄.

FIG. 13 is a configuration diagram of the latch unit **1004-002**. D flip-flops **1302-1** to **1302-4** and latch circuits **1301-1** to **1301-4** operate in accordance with the clock signal from the signal line CLK. The image data from the signal lines PDATA₄ to PDATA₁ and a second latch signal from a signal line LAT₂ are input to the latch circuits **1301-1**

to **1301-4**. Upon receiving the second latch signal from the signal line LAT₂, the latch circuits **1301-1** to **1301-4** latch the values being output to the signal lines PDATA₄ to PDATA₁ at that time, and output drive signals based on the latched values to the signal lines PON₂₋₄ to PON₂₋₁, as illustrated in FIG. 14. That is, the latch circuits **1301-1** to **1301-4** store the input image data, and output drive signals based on the stored image data. In other words, the latch circuits **1301-1** to **1301-4** correspond to a second data storage unit, or a plurality of data storage units. Furthermore, the second latch signal corresponds to a second trigger signal. The drive signals each output to the signal lines PON₂₋₄ to PON₂₋₁ are drive signals of the light emitting points **602** located next (right side in FIG. 5) in the main scan direction to the light emitting point **602** driven by the drive signals output to the signal lines PON₁₋₄ to PON₁₋₁. In other words, the drive signals output to the signal lines PON₂₋₄ to PON₂₋₁ are drive signals of each second light emitting point **602** of the four sets. According to FIG. 14, the signal lines PON₂₋₁ to PON₂₋₄ output drive signals based on the pieces of image data D₅ to D₈. The drive signals are input to the current drive unit **1104**. The latch units **1004-002** maintains outputting the drive signals based on the pieces of image data D₅ to D₈ until receiving a second latch signal based on the next line synchronization signal. In other words, the drive signal based on the pieces of image data D₅ to D₈ are output for the duration of two consecutive line synchronization signals (about 105.8 μ s in the present example). In addition, the latch unit **1004-002** delays the second latch signal by the D flip-flops **1302-1** to **1302-4**, and outputs a third latch signal to a signal line LAT₃ at a timing when the transfer unit **1003** outputs the piece of image data D₁₂ to the signal line PDATA₄.

The same goes for the operation of the latch units **1004-003** to **1004-748**. In summary, each of the latch units **1004-m** (m being an integer from 1 to 748) includes four latch circuits. The four latch circuits of the latch unit **1004-m** each latch the pieces of image data D_(4m), D_(4m-1), D_(4m-2), and D_(4m-3) based on the m-th latch signal, and output drive signals based on the latched image data to the current drive unit **1104** for the duration of two consecutive line synchronization signals. Here, the four latch circuits of the latch unit **1004-m** correspond to the m-th light emitting point **602** among the 748 light emitting points **602** arranged along the main scan direction of each of the first to the fourth sets. In other words, the four latch circuits of the latch unit **1004-m** output the drive signals of the m-th light emitting point **602** of each of the first to the fourth sets. In addition, the latch units **1004-m** except for m=748 generate an (m+1)-th latch signal based on the m-th latch signal and output the (m+1)-th latch signal to the latch unit **1004-(m+1)**. As such, each of the latch units **1004-001** to **1004-748** outputs a drive signal for controlling emission/non-emission of light of each light emitting point **602** to the current drive unit **1104** for the duration of two consecutive line synchronization signals. In other words, the transfer unit **1003** and the latch units **1004-001** to **1004-748** correspond to a signal output unit. In addition, the latch circuits **1101-5** to **1101-8** included in the transfer unit **1003** and the latch circuits **1202-1** to **1202-4** included in the latch unit **1004** correspond to a signal output circuit.

FIG. 17 illustrates a relation between the line synchronization signal of the signal line SYNC, the first latch signal and the second latch signal of the signal lines LAT₁ and LAT₂, and the drive signals output to the signal lines PON₁₋₁ to PON₁₋₄ and PON₂₋₁ to PON₂₋₄. The cycle of the line synchronization signal is about 105.8 μ s as described

above. The cycles of the first latch signal and the second latch signal are about 105.8 μ s, which is same as that of the line synchronization signal. The timing of the second latch signal is behind the first latch signal by four clocks. More generally, the timing of the (q+1)-th latch signal (q being an integer from 1 to 747) is behind the q-th latch signal by four clocks.

The transfer unit 1003 sequentially receives the pieces of image data D1[1] to D2992[1] in synchronization with an initial line synchronization signal illustrated in FIG. 17. In addition, the transfer unit 1003 sequentially receives the pieces of image data D1[2] to D2992[2] in synchronization with a second line synchronization signal illustrated in FIG. 17. The four latch circuits of the latch unit 1004-001 output drive signals, based on the pieces of image data D1[1] to D4[1], to the signal lines PON1-1 to PON1-4 from the timing of the first latch signal based on the initial line synchronization signal illustrated in FIG. 17. Output of drive signals based on the pieces of image data D1[1] to D4[1] continues until a first latch signal based on the second line synchronization signal is received. Upon receiving the first latch signal based on the second line synchronization signal, the four latch circuits of the latch unit 1004-001 output drive signals based on the pieces of image data D1[2] to D4[2] to the signal lines PON1-1 to PON1-4. Similarly, the four latch circuits of the latch unit 1004-002 output drive signals based on the pieces of image data D5[1] to D8[1] to the signal lines PON2-1 to PON2-4 from the timing of the second latch signal based on the initial line synchronization signal. Output of drive signals based on the pieces of image data D5[1] to D8[1] continues until a second latch signal based on the second line synchronization signal is received. Upon receiving the second latch signal based on the second line synchronization signal, the four latch circuits of the latch unit 1004-002 output drive signals based on the pieces of image data D5[2] to D8[2] to the signal lines PON2-1 to PON2-4. The same goes for the latch units 1004-003 to 1004-748. In other words, each of the latch units 1004 are cascade-connected to each other such that they can sequentially transmit latch signals.

Here, the cycle of the line synchronization signal is longer than the time required for transmitting latch signals corresponding to all of the light emitting elements, and therefore all of the latch signals are output in a period from when a line synchronization signal is transmitted to when a next line synchronization signal is transmitted. Since the light emitting points 602 are sequentially driven in a state where the timing of starting the light emission is shifted for each of the four light emitting points, it is possible to reduce the noise generated at turning on the light emitting points, in comparison to the case of simultaneously turning on all the light emitting points. Furthermore, the output to the current drive unit 1104 is performed for the duration of two consecutive line synchronization signals.

In the present embodiment, the transfer unit 1003 and the latch unit 1004 form an output unit that receives image data corresponding to each of the plurality of light emitting points 602, and outputs a drive signal for the corresponding light emitting point 602 based on the received image data. More specifically, each of the 748 latch units 1004-001 to 1004-748 of the present embodiment includes four latch circuits, and therefore the output unit includes a total of 2992 latch circuits. Each latch circuit corresponds to one of the 2992 light emitting points 602 included in one light emitting chip 400. Each latch circuit latches image data of the

corresponding light emitting point 602, and outputs a drive signal for the corresponding light emitting point 602 based on the latched image data.

FIG. 15 illustrates a configuration of the current drive unit 5 1104. Here, FIG. 15 illustrates only a part of the circuit corresponding to one light emitting point 602. The light emitting chip 400 according to the present embodiment include a total of 2992 light emitting points 602, and therefore the light emitting chip 400 include 2992 circuit units illustrated in FIG. 15. ADAC 1501 outputs an analog voltage in accordance with a digital value indicated by the control data stored in the register 1102. In an FET 1502, which is a P-channel MOSFET, a source terminal is connected to a power supply voltage VCC and a drain terminal 10 is connected to a source terminal of an FET 1503. The analog voltage output by the DAC 1501 is applied to the gate terminal of the FET 1502. Further, in the FET 1503, which is also a P-channel MOSFET, a drain terminal is connected to the lower electrode 504. The drive signal output from the 15 image data holding unit 1103 is input to the gate terminal of the FET 1503 via a switching circuit 1504. The drive signal 20 is a one-bit binary signal of a high level or a low level, and the FET 1503 is on during the high level, and the FET 1503 is off during the low level.

25 While FET 1503 is on, electric current flows from the power supply voltage VCC to the light emitting layer 506 via FET 1502 and FET 1503 and thus the light emitting point 602 emits light. The light emission intensity of the light emitting point 602 varies in accordance with the current flowing through the light emitting layer 506, and the value of the current is controlled by an analog voltage output from the DAC 1501. In other words, the light emission intensity of each of the light emitting points 602 is controlled by the control data stored in the register 1102. Here, the control 30 data may individually indicate a digital value of each DAC 1501 corresponding to respective light emitting points 602, or may indicate one digital value for each group of the plurality of light emitting points 602.

35 Here, the switching circuit 1504 is provided to switch between a normal state, in which the drive signal is applied to the gate terminal of the FET 1503, and a test state. In the test state, the switching circuit 1504 applies a high level signal to the gate terminal of the FET 1503, forcibly causing the FET 1503 to be on state. Here, the switching between the 40 normal state and the test state is also performed based on control data stored in the register 1102. The test state maybe used to cause any of the light emitting points 602 to emit light in manufacturing of the exposure head 106.

FIG. 16 is a flowchart of processing executed by the 45 image controller 700 when a print request is issued from a user. At S10, the image controller 700 writes, to the register 1102 of each of the light emitting chips 400, control data for making the state of each switching circuit 1504 to be the normal state. At S11, the image controller 700 sets, in the 50 register 1102 of each of the light emitting chips 400, a digital value to be set in the DAC 1501 corresponding to each light emitting point 602. Subsequently, at the start timing of image formation, the image controller 700 transmits an image data at S12 and starts exposing the photoconductor 55 102. The image controller 700 determines at S13 whether or not the image formation is completed, and when the image formation is not completed, repeats the processing from S12. When, on the other hand, the image formation is completed, the image controller 700 terminates the processing of FIG. 60 13.

65 Here, when each light emitting point 602 is made to emit light in manufacturing of the exposure head 106, the image

controller 700 first sets, in the register 1102, a digital value to be set in the DAC 1501 corresponding to the target light emitting point 602. Subsequently, the image controller 700 writes, to the register 1102, control data for making the state of the switching circuit 1504 to be in the test state. After completion of the test, the image controller 700 writes control data for making the state of the switching circuit 1504 to be the normal state. Here, a configuration of making the light emitting points 602 to be the test state may be a configuration in which each light emitting point 602 is independently specified, or a configuration in which each light emitting point group including two or more light emitting points 602 is specified, for example, all the light emitting points 602 are collectively specified.

As has been described above, the latch unit 1004-m in the present embodiment latches the pieces of image data D(4m), D(4m-1), D(4m-2) and D(4m-3) when the m-th latch signal is input, and outputs a drive signal based on the latched image data to the current drive unit 1104. Such a configuration allows for turning on the plurality of light emitting units 602, based on the image data transmitted in serial communication, without providing flip-flop circuits, configured to transfer the input image data in the main scan direction, in number corresponding to the number of light emitting units. In other words, increase in size of the light emitting chips or increase in cost of the light emitting chips due to the flip-flop circuits, configured to transfer the input image data in the main scan direction, being provided in number corresponding to the number of the light emitting units can be prevented. In other words, increase in size and in cost of the light emitting chips can be prevented more than the related art.

Generally, the amount of light emitted by organic EL film is smaller than the amount of light emitted by an LED formed by using gallium arsenide or the like, for example. In the present embodiment, drive signals for controlling emission/non-emission of light of each light emitting point 602 are output to the current drive unit 1104 for the duration of two consecutive line synchronization signals. That is, in the present embodiment, the light emitting point 602 may emit light for the duration of two consecutive line synchronization signals. As a result, exposing time for the photoconductor 102 can be made longer than a configuration in which the light emitting point 602 emits light for only a part of the duration of two consecutive line synchronization signals. As a result, the photoconductor 102 can be sufficiently exposed to form a toner image, whereby the toner image is appropriately formed on the photoconductor 102. In other words, it is possible to prevent a case in which the photoconductor 102 is not sufficiently exposed to form a toner image due to the light emitting point 602 only emitting light for a part of the duration of two consecutive line synchronization signals.

When the FET 1503 is made to be on, there is a possibility that the power line voltage may fluctuate due to the light emitting point 602 being supplied with the current output from the power supply VCC, and thus radiation noise may be generated from the power line. In the present embodiment, the light emitting points 602 are sequentially turned on four by four, instead of simultaneously turning on all the light emitting points 602 provided in the light emitting chips 400. As a result, voltage fluctuation of the power line is prevented in comparison with the case of simultaneously turning on the FET 1503 corresponding to each of the light emitting points 602 in order to simultaneously turn on all the

light emitting points 602 provided in the light emitting chips 400. As a result, the radiation noise generated from the power line can be reduced.

In addition, the light emission periods of the light emitting points 602 adjacent to each other in the main scan direction overlap with each other, in the duration of two consecutive line synchronization signals. When the light emission start timings of the light emitting points 602 are largely different, exposure positions of the light emitting points 602 in the sub scan direction may be largely different. By overlapping the exposure periods of the light emitting points 602 with each other, exposure time of the photoconductor 102 can be secured and the risk of misalignment of exposure positions in the sub scan direction for each light emitting point can be reduced.

Here, in the present embodiment, one light emitting chip 400 includes four sets of 748 light emitting points 602 arranged along the main scan direction. Accordingly, a total of 2992 latch circuits corresponding to each light emitting point 602 are grouped by each four latch circuits, which number corresponds to the number of sets, into a total of 748 groups, and one latch unit 1004 is provided for each corresponding group. In addition, since one group includes four latch circuits, the transfer unit 1003 sequentially transfers the image data to the four signal lines PDATA1 to PDATA4. However, for example, the number of latch circuits included in one group may be an integer multiple of the number of sets. For example, when the number of latch circuits included in one group is set to be twice the number of sets for the light emitting chips 400 including four sets of 748 light emitting points 602 arranged along the main scan direction, the number of groups is 374, and the number of latch units 1004 is 374. Additionally in this case, the transfer unit 1003 sequentially transfers the image data to eight signal lines. In the present invention, the number of latch circuits included in one group is not limited to an integer multiple of the number of sets, and may be, for example, one over an integer of the number of sets. In addition, the number of latch circuits included in one group may be set irrespective of the number of sets. Furthermore, the number of light emitting points 602 (or the number of latch circuits) included in each group may not be the same. In other words, the number of light emitting points 602 (or the numbers of latch circuits) included in each group may be any number equal to or larger than one.

Although specific numerical values are used for description in the aforementioned embodiment, the specific numerical values are merely exemplary and the present invention is not limited to any specific numerical values used in the embodiment. Specifically, the number of the light emitting chips 400 provided on one printed substrate 202 is not limited to 20, and may be any number equal to or larger than one. In addition, the number of light emitting points 602 included in each of the light emitting chips 400 is not limited to 2992 and may be other numbers. Further, in the present embodiment, one light emitting chip 400 includes four sets of 748 light emitting points arranged along the main scan direction, the number of sets may be any number equal to or larger than one. In addition, the light emitting points 602 are arranged in the main scan direction at a pitch of about 21.16 μm , which corresponds to the resolution of 1200 dpi, the arrangement interval of the light emitting points 602 may be other values.

Further, in the aforementioned embodiment, the image forming apparatus transfers the toner image formed on each photoconductor 102 onto the sheet conveyed on the transfer belt 111. However, the image forming apparatus may trans-

fer the toner image of each photoconductor 102 onto the sheet via an intermediate transfer member. In addition, the image forming apparatus may be a color image forming apparatus that forms an image using toner of a plurality of colors, or a monochrome image forming apparatus that forms an image using toner of one color.

Other Embodiments

Embodiment(s) of the present invention can also be realized by a computer of a system or apparatus that reads out and executes computer executable instructions (e.g., one or more programs) recorded on a storage medium (which may also be referred to more fully as a ‘non-transitory computer-readable storage medium’) to perform the functions of one or more of the above-described embodiment(s) and/or that includes one or more circuits (e.g., application specific integrated circuit (ASIC)) for performing the functions of one or more of the above-described embodiment(s), and by a method performed by the computer of the system or apparatus by, for example, reading out and executing the computer executable instructions from the storage medium to perform the functions of one or more of the above-described embodiment(s) and/or controlling the one or more circuits to perform the functions of one or more of the above-described embodiment(s). The computer may comprise one or more processors (e.g., central processing unit (CPU), micro processing unit (MPU)) and may include a network of separate computers or separate processors to read out and execute the computer executable instructions. The computer executable instructions may be provided to the computer, for example, from a network or the storage medium. The storage medium may include, for example, one or more of a hard disk, a random-access memory (RAM), a read only memory (ROM), a storage of distributed computing systems, an optical disk (such as a compact disc (CD), digital versatile disc (DVD), or Blu-ray Disc (BD)^{TM}), a flash memory device, a memory card, and the like.

While the present invention has been described with reference to exemplary embodiments, it is to be understood that the invention is not limited to the disclosed exemplary embodiments. The scope of the following claims is to be accorded the broadest interpretation so as to encompass all such modifications and equivalent structures and functions.

This application claims the benefit of Japanese Patent Application No. 2022-132718, filed Aug. 23, 2022, which is hereby incorporated by reference herein in its entirety.

What is claimed is:

1. A light emitting chip comprising:

- a light emitting unit array including a plurality of light emitting units arranged in a predetermined direction;
- an image data input terminal configured to be input with image data;
- a first data storage unit configured to store data, input from the image data input terminal, for causing a first light emitting unit included in the plurality of light emitting units to emit light;
- a second data storage unit configured to store data, input from the image data input terminal, for causing a second light emitting unit included in the plurality of light emitting units to emit light;
- a signal output unit configured to output a first trigger signal and a second trigger signal delayed with respect to the first trigger signal; and
- a drive unit configured to drive the first light emitting unit, in a case where the first trigger signal is output, based on data stored in the first data storage unit, and drive the

second light emitting unit, in a case where the second trigger signal is output, based on data stored in the second data storage unit.

2. The light emitting chip according to claim 1, wherein 5 the signal output unit outputs the first trigger signal and the second trigger signal at a predetermined cycle, and

wherein the drive unit drives the first light emitting unit, based on data stored in the first data storage unit, in a period from when the first trigger signal is output to when the next first trigger signal is output, and drives the second light emitting unit, based on data stored in the second data storage unit, in a period from when the second trigger signal is output to when the next second trigger signal is output.

3. The light emitting chip according to claim 1, wherein 15 the light emitting chip includes a synchronization signal input terminal configured to be input with a synchronization signal at a predetermined cycle, and

wherein the signal output unit outputs the first trigger signal based on the synchronization signal.

4. The image forming apparatus according to claim 3, 20 wherein the plurality of light emitting units emit light for exposing a photoconductor that is rotating, and

wherein the predetermined cycle is a cycle in which the photoconductor rotates by a resolution in a circumferential direction of the photoconductor in the image data.

5. The light emitting chip according to claim 1, wherein 25 the light emitting chip includes a synchronization signal input terminal configured to be input with a synchronization signal at a predetermined cycle, and

wherein the signal output unit outputs the first trigger signal and the second trigger signal in a period from when the synchronization signal is input to when the next synchronization signal is input.

6. The light emitting chip according to claim 1, wherein 30 when the data stored in the first data storage unit indicates light emission of the first light emitting unit, and the data stored in the second data storage unit indicates light emission of the second light emitting unit, there is an overlap between a period in which the drive unit drives the first light emitting unit in response to the first trigger signal and the first light emitting unit emits light and a period in which the drive unit drives the second light emitting unit in response to the second trigger signal and the second light emitting unit emits light.

7. The light emitting chip according to claim 1, wherein 35 the light emitting chip includes a third data storage unit configured to store data, input from the image data input terminal, for causing a third light emitting unit included in the plurality of light emitting units to emit light,

wherein the signal output unit includes a first signal output circuit configured to output the first trigger signal, a second signal output circuit configured to output the second trigger signal based on the first trigger signal, and a third signal output circuit configured to output a third trigger signal based on the second trigger signal,

wherein the drive unit drives the third light emitting unit, in a case where the third trigger signal is output, in accordance with data stored in the third data storage unit, and

wherein the first signal output circuit, the second signal output circuit, and the third signal output circuit are cascade-connected.

8. The light emitting chip according to claim 1, wherein 60 the plurality of light emitting units is organic EL.

15

9. A light emitting chip comprising:
 a light emitting unit array including a plurality of light emitting units arranged in a predetermined direction;
 an image data input terminal configured to be input with image data;
 a signal output unit configured to output trigger signals respectively corresponding to the plurality of light emitting units, with output start timings of respective trigger signals output by the signal output unit being different from each other;
 a plurality of data storage units provided respectively corresponding to the plurality of light emitting units and configured to store data input from the image data input terminal, each of the plurality of data storage units being configured to output stored data in a case 15 where a corresponding trigger signal is output; and
 a drive unit configured to drive the plurality of light emitting units based on data output from the plurality of data storage units.

10. The light emitting chip according to claim 9, wherein the signal output unit outputs each trigger signal at a predetermined cycle, and

wherein the drive unit drives each of the plurality of light emitting units based on data corresponding to the trigger signal stored in the data storage unit in a period 25 from when the trigger signal is output to when the next trigger signal is output.

11. The light emitting chip according to claim 9, wherein the light emitting chip includes a synchronization signal input terminal configured to be input with a synchronization signal at a predetermined cycle, and

wherein the signal output unit outputs at least one of the trigger signals based on the synchronization signal.

12. The light emitting chip according to claim 11, wherein the plurality of light emitting units emit light for exposing a 35 photoconductor that is rotating, and

wherein the predetermined cycle is a cycle in which the photoconductor rotates by a resolution in a circumferential direction of the photoconductor in the image data.

13. The light emitting chip according to claim 9, wherein the light emitting chip includes a synchronization signal input terminal configured to be input with a synchronization signal at a predetermined cycle, and

wherein the signal output unit outputs each of the trigger 45 signals in a period from when the synchronization signal is input to when the next synchronization signal is input.

14. The light emitting chip according to claim 9, wherein, among the plurality of light emitting units, each of the plurality of light emitting units driven based on the data indicating light emission has a light emitting period that overlaps with each other.

15. The light emitting chip according to claim 9, wherein the signal output unit includes a plurality of signal output

16

circuits configured to output the trigger signal respectively corresponding to the plurality of light emitting units, and wherein each of the plurality of signal output circuits is cascade-connected.

16. The light emitting chip according to claim 9, wherein the plurality of light emitting units is organic EL.

17. An image forming apparatus comprising:

a photoconductor; and
 a light emitting chip comprising:

a light emitting unit array including a plurality of light emitting units arranged in a predetermined direction; an image data input terminal configured to be input with image data;

a first data storage unit configured to store data, input from the image data input terminal, for causing a first light emitting unit included in the plurality of light emitting units to emit light;

a second data storage unit configured to store data, input from the image data input terminal, for causing a second light emitting unit included in the plurality of light emitting units to emit light;

a signal output unit configured to output a first trigger signal and a second trigger signal delayed with respect to the first trigger signal; and

a drive unit configured to drive the first light emitting unit, in a case where the first trigger signal is output, based on data stored in the first data storage unit, and drive the second light emitting unit, in a case where the second trigger signal is output, based on data stored in the second data storage unit.

18. An image forming apparatus comprising:

a photoconductor; and

a light emitting chip comprising:

a light emitting unit array including a plurality of light emitting units arranged in a predetermined direction; an image data input terminal configured to be input with image data;

a signal output unit configured to output trigger signals respectively corresponding to the plurality of light emitting units, output start timings of respective trigger signals output by the signal output unit being different from each other;

a plurality of data storage units provided respectively corresponding to the plurality of light emitting units and configured to store data input from the image data input terminal, each of the plurality of data storage units being configured to output stored data in a case where a corresponding trigger signal is output; and

a drive unit configured to drive the plurality of light emitting units based on data output from the plurality of data storage units.
